(57) **CLAIM**

I claim the ornamental design for support structure for grill, as shown and described.

DESCRIPTION

FIG. 1 is a perspective view of the support structure for grill, showing my new design;

FIG. 2 is a front view of the support structure for grill of FIG. 1;

FIG. 3 is a rear view of the support structure for grill of FIG. 1;

FIG. 4 is a left side view support structure for grill of FIG. 1;

FIG. 5 is a right side view support structure for grill of FIG. 1;

FIG. 6 is a top view of the support structure for grill of FIG. 1;

FIG. 7 is a bottom view of the support structure for grill of FIG. 1; and,

FIG. 8 is a rear perspective view of the support structure for grill, showing my new design.

The broken lines in FIGS. 1 through 8 are shown for the purpose of illustrating parts of the article that form no part of the claimed design.
